(57) **CLAIM**

The ornamental design for a skyrocket, as shown and described.

DESCRIPTION

FIG. 1 is a prospective view of the skyrocket of the present invention, a guide stick being shown in dashed lines for showing the environment of use and not forming a part of the design hereof;

FIG. 2 is a front elevational view thereof;

FIG. 3 is a left side elevational view, the right side elevational view being a mirror image thereof;

FIG. 4 is a rear elevational view thereof;

FIG. 5 is a top plan view thereof; and,

FIG. 6 is a bottom view thereof.
